(57) CLAIM

The ornamental design for a label for a bottle, as shown and described.

DESCRIPTION

FIG. 1 is a front view of a label for a bottle showing the new design; and,

1 Claim, 1 Drawing Sheet

FIG. 2
